UNITED STATES PATENT OFFICE.

FREDERICK W. KRONENBERG, OF PHILADELPHIA, PENNSYLVANIA.

DOWNSHOT STEAM GENERATOR.

Application filed April 15, 1922. Serial No. 552 854.

My invention relates to a new and useful improvement in downflow steam generators, and has for its object to so construct and combine a horizontal header with the lower sets 5 of tubes of such a generator as to permit the free circulation and equalization of the water at the lowest point whereby the tubes and other parts of the generator subjected to the greatest heat of the furnace will be protected 10 against burning or other injury.

A further object of the invention is to so construct this horizontal header that it will provide for the reception of both the downflow tubes and the upflow tubes and form a 15 horizontal chamber the full width of the bank of tubes of a capacity to carry sufficient water for readily equalizing the water in all the tubes leading thereto or connected therewith.

With these ends in view, this invention consists in the details of construction and combination of elements hereinafter set forth and then specifically designated by the 20 claims.

In order that those skilled in the art to 25 which this invention appertains, may understand how to make and use the same, I will describe its construction in detail, referring by numerals to the accompanying drawings forming a part of this application, in 30 which:—

Fig. 1, is a vertical section or portion of a steam generator having my improvements embodied therein.

Fig. 2, is a front view of the header.

Fig. 3, is a plan view thereof.

Fig. 4, is an enlarged fragmental view of a portion of the header.

Fig. 5, is a section at the line 5—5 of Fig. 4.

Fig. 6, is a section at the line 6—6 of Fig. 4.

40 In carrying out my invention as here embodied, 1 represents the setting of a boiler in which is mounted the drum 2 and from the lower portion of one end of the drum down-take tubes 3 lead (but one of said tubes being 45 here shown), and these tubes are connected by a coupler 4 to the first series of downflow tubes 5 which are in turn connected with the second set of downflow tubes 6 and these in turn are connected with the bottom downflow 50 tubes 7.

8 represents the horizontal header which is cast in one piece and has a chamber 9 formed therein throughout the length there-

of. Formed with this horizontal header are a number of boxes 10, the interior space of each box being in open communication with the chamber 9.

Each of the boxes 10 has formed therein an opening 11 for the reception of the lowest end of one of the downflow tubes 7 and also 60 an opening 12 for a suitable handhold plate, here not shown. In the header beneath each box are formed two openings 13 for suitable handhold plates and directly opposite these openings are corresponding openings 14 for the reception of the lowest ends of the upflow tubes 15, the latter being expanded or otherwise secured in the header and extending on an incline rearward and upward and in the furnace 16 and connected by the couplers 17 70 to the uptake tube 18 leading to the coupler 19, the latter being connected by the nipple or short tube 20 with the drum 2 above the water level thereof.

21 is a drain formed with the header and 75 may have connected therewith any suitable control valve.

In practice when my improved header is combined with a steam generator of the character described, the water and steam pressure 80 in all of the tubes is equalized since the header forms an open free communication between the lowest ends of the tubes while the drum 2 forms an open free communication between the upper ends thereof, thus preventing any 85 unequal action throughout the system and facilitating the circulation of the water downward through the header and upward therefrom.

I prefer to place a baffle 22 between the 90 series of tubes 7 and 15 so that while exposing the tubes 15 to the direct action of the fire the tubes 7 will be less exposed thereto, thus intensifying the steaming capacity of the tubes 15 and as they are inclined upward from the header, which latter is the lowest point in the system the water will be forced to flow upward from the header through the tubes 15 95 at high speed.

By providing free communication between 100 the tubes through the header a generator constructed in accordance with my improvement is especially adapted for marine work since the roll of a vessel will not displace the water within any of the tubes and therefore 105 not expose said tubes to undue temperatures.

In order that the proper direction may be given to the products of combustion I provide the baffles 22 and 24 but of course any number of baffles may be used and so placed as to produce the desired results.

Of course I do not wish to be limited to the exact details of construction as herein shown as these may be varied within the limits of the appended claims without departing from 10 the spirit of my invention.

Having thus fully described my invention, what I claim as new and useful is:—

1. In a downflow steam generator, a header comprising a longitudinally extending body having a chamber extending throughout its entire length, a series of spaced outflow openings through a side wall of said body arranged in pairs for connecting upflow tubes with said chamber, and a series of boxes 15 corresponding in number to the number of pairs of outflow openings superposed on said body, each box having an opening for connection with a downflow tube and opening into said chamber to the space between the two openings of the underlying pair of outflow openings, the top wall of each outflow opening being closely adjacent the top wall of said body, 20 and a series of boxes corresponding in number to the number of pairs of outflow openings superposed on said body, each box having an opening for connection with a downflow tube and opening into said chamber to the space between the two openings of the underlying pair of outflow openings, the top wall of each outflow opening being closely adjacent the top wall of said body, 25

whereby communication between adjacent boxes is baffled.

2. In combination with a downflow steam generator, having a drum, a header comprising a longitudinally extending body having a chamber extending throughout its entire length, a series of spaced outflow openings through a side wall of said body arranged in pairs for connecting upflow tubes with said chamber, and a series of boxes corresponding in number to the number of pairs of outflow openings superposed on said body, each box having an opening for connection with a downflow tube and opening into said chamber to the space between the two openings of the underlying pair of outflow openings, the top wall of each outflow opening being closely adjacent the top wall of said body, whereby communication between adjacent boxes is baffled, a series of downflow tubes communicating with said drum and said header boxes, and a series of upflow tubes communicating with said header chamber and said drum. 40

In testimony whereof, I have hereunto affixed my signature.

FREDERICK W. KRONENBERG.
